ABSORPTION REFRIGERATING SYSTEM OF
THE UNIFORM PRESSURE TYPECharles A. Miller, Evansville, Ind., assignor to
Servel, Inc., New York, N. Y., a corporation of
Delaware

Application December 8, 1947, Serial No. 790,367

8 Claims. (Cl. 62—119.5)

1

This invention relates to refrigeration and particularly to absorption refrigerating systems of the uniform pressure type.

It is an object of this invention to provide an improved arrangement and location of several elements of a refrigerating system relative to a refrigerator cabinet.

In absorption refrigerating systems of the uniform pressure type wherein the interior or food storage space of the refrigerator cabinet is divided into a plurality of compartments cooled to different temperatures it is often desirable that the freezing section of the evaporator be placed in an upper part of the cabinet. This is particularly true when the freezing section comprises a relatively flat horizontal member which traverses substantially the entire width and depth of the interior of the cabinet and forms the bottom of a freezing compartment in the upper part of the cabinet. However, with uniform pressure absorption refrigerating systems wherein an inert gas storage or pressure vessel is used it is desirable that such pressure vessel be located at an elevation such that condensate formed therein will drain into an upper part of the evaporator. It is also desirable, and in fact necessary, that the pressure vessel be cooled in some manner so that refrigerant vapor conveyed thereto will be condensed therein.

Heretofore when it was desired that condensate formed in the pressure vessel drain therefrom into the evaporator, the pressure vessel has been located in the flue at the rear of the cabinet at an elevation above the condenser. In gravity flow system, such location of the pressure vessel limits the height at which the condenser may be placed in the flue, which in turn limits the height at which the evaporator may be placed in the food storage compartment. The pressure vessel may be placed within the flue below the condenser and still drain into the upper part of the evaporator. However, placing of the pressure vessel in the flue below the condenser obstructs the flow of cooling air over the condenser and thereby reduces the efficiency of the refrigerating system. Furthermore, it is desirable that liquid refrigerant conveyed from the condenser to the upper part of the evaporator be precooled before such refrigerant enters the evaporator. This may be accomplished by locating the drain conduit between the condenser and the evaporator in the flue. But here again the location of this drain in the flue obstructs passage of cooling air over the condenser.

In accordance with my invention, I provided

2

an arrangement whereby the condenser is placed in the uppermost part of the flue so that a flat horizontal low-temperature evaporator may be placed in a relatively high position in the food storage compartment of the refrigerator and still have a sufficient drop between the condenser and inlet of the evaporator for gravity flow of liquid refrigerant from the former to the latter. I also provide an arrangement whereby the pressure vessel, which in my case constitutes a horizontally elongated vessel, is placed in the upper part of a double wall insulated closure member, which closure member forms a portion of the rear wall of the refrigerator cabinet. The closure member is provided with the usual metal mounting plate, which mounting plate forms a part of the vertical flue at the rear of the refrigerator cabinet. The pressure vessel is arranged to receive uncondensed refrigerant vapor from the outlet of the condenser, and the pressure vessel is mounted in good thermal contact with the metal mounting plate, whereby refrigerant vapor conveyed to the pressure vessel is condensed therein, the condensate formed thereby is conveyed by gravity flow to the uppermost part of the evaporator and the heat of condensation is transmitted from the pressure vessel through the metal mounting plate to air flowing upward in the vertical flue without interfering with the passage of air over the condenser.

The conduit which conveys the liquid refrigerant from the condenser to the evaporator is also located within the closure member and a portion of this conduit is mounted in good thermal contact with the metal mounting plate, whereby liquid refrigerant passing from the condenser to the evaporator through this conduit is cooled by heat transfer from the conduit through the mounting plate to air flowing upward through the flue. Another portion of the conduit which conveys liquid refrigerant from the condenser to the evaporator is mounted in good thermal contact with the rich or cold gas side of a gas heat exchanger, which gas heat exchanger is also located within the double wall closure member.

With the above arrangement, the condenser is so mounted in the flue that liquid refrigerant flows therefrom into a low-temperature section of the evaporator which section is located at a relatively high level in the food storage compartment of the refrigerator, the pressure vessel is arranged below the condenser in a manner that heat is transferred from the pressure vessel to air passing through the flue without interfering

55 with the cooling of the condenser, while at the

same time discharging condensate from the pressure vessel to the evaporator, and liquid refrigerant conveyed from the condenser to the evaporator is precooled without interfering with the passage of cooling air over the condenser.

The invention together with the above and other objects and advantages will be more clearly understood from the following detailed description, taken in connection with the accompanying drawings, wherein:

Fig. 1 is a view diagrammatically illustrating a refrigerating system incorporating my invention.

Fig. 2 is a side elevational view, partly in section, of a refrigerator incorporating my invention.

Fig. 3 is a front elevational view of the upper half of the refrigerator shown in Fig. 2.

Fig. 4 is a transverse sectional view taken on line 4—4 of Fig. 2.

Fig. 5 is a rear elevational view looking in the direction of the arrows 5—5 in Fig. 2.

Referring to Fig. 1, for purposes of illustration, I have incorporated my invention in a uniform pressure absorption refrigerating system of the gravity flow type, which system includes generally, a generator 10, a condenser 11, an evaporator 12, an absorber 13 and conduits interconnecting said elements for flow of a refrigerating medium, an absorption liquid and a pressure-equalizing gas. The system contains, for example, a solution of refrigerant in absorption liquid, such as ammonia in water, and an auxiliary inert gas, such as hydrogen.

The generator 10 comprises a substantially horizontal shell divided into chambers 14 and 15 and having an upright portion or standpipe 16. The lower end of standpipe 16 is connected to chamber 15. Chamber 14 is provided with a dome 17. A riser or vapor-lift conduit 18 is connected from chamber 14 to the upper part of standpipe 16. The lower end of conduit 18 extends downward through the dome 17 into chamber 14. The generator is heated by any suitable means, as by a gas burner 19 arranged so that the flame therefrom is projected into the lower end of a flue 20 which extends concentrically through the shell of the generator. The upper end of standpipe 16 is connected by a vent conduit 21 and a conduit 22 to the lower end of an analyzer 23. The upper end of the analyzer is connected by a conduit 24 to the upper or inlet end of condenser 11. The outlet end of the condenser is connected by a conduit 25 to a freezing section 12^a of the evaporator 12.

Chamber 15 of the generator is connected by a conduit 26, a lower portion of vent conduit 21, an inner passage 27 of a liquid heat exchanger 28 and a conduit 29 to the upper part of absorber 13. As shown, conduit 26 passes through the analyzer 23. The lower end of the absorber is connected to chamber 14 of the generator by an absorber vessel 30, a conduit 31 forming the outer passage of liquid heat exchanger 28, a conduit 32, analyzer 23 and a conduit 33.

The upper part of the absorber 13 is connected by a conduit 34, an outer passage 35 of an auxiliary gas heat exchanger 36, a conduit 37, an inner passage 38 of main gas heat exchanger 39, and a conduit 40 to the inert gas inlet end of freezing section 12^a of the evaporator. The inert gas outlet end of freezing section 12^a is connected by a conduit 48 to a box cooling section 12^b of the evaporator, which latter section is connected by a conduit 41, an outer passage 42 of the main gas heat exchanger, a conduit 43 which forms the inner

passage of the auxiliary gas heat exchanger 36, a conduit 44, and absorber vessel 30 to the lower part of absorber 13. Auxiliary gas heat exchanger 36 is provided at its lower end with a liquid trap 45 for conveying liquid from the outer passage 35 of this heat exchanger into conduit 44.

As shown, absorber 13 includes an upper section 13^a into one end of which section conduit 29 is connected and at the opposite end of which section a conduit 46 connects with the next lower section 13^b of the absorber. A pressure vessel 47 is connected at one end to conduit 25 by a conduit 48, and at its opposite end the pressure vessel is connected by a conduit 49 to the outer passage 42 of gas heat exchanger 39.

Referring now to Figs. 2 and 5 of the drawings, in accordance with my invention, the condenser 11 includes two horizontal rows of tubes provided with heat transfer fins 11^a and fitted into the upper portion of a vertical flue D at the rear of the refrigerator. A metal mounting plate 50 forms the outer wall of a double wall insulated closure member 51, which closure member forms a part of the rear wall of the refrigerator, and which mounting plate forms a part of the vertical flue. Pressure vessel 47 is mounted in the upper portion of the closure member 51 and is welded along its length to mounting plate 50, as at 47^a. Conduit 25 which delivers refrigerant from the condenser to the freezing section 12^a of the evaporator is welded, as at 25^a, to the mounting plate 50, and, as at 25^b, to the outer surface of main liquid heat exchanger 39. Closure member 51 is provided with suitable insulation, not shown. Only so much of the refrigerating system as is necessary for a complete understanding of my invention has been shown in Figs. 2 and 5.

As shown in Figs. 2 and 3, the freezing section 12^a and the box cooling section 12^b of the evaporator are so arranged within the refrigerator cabinet as to provide an ice freezing compartment A, a low-temperature or frozen food compartment B and a food storage compartment C. Frozen food compartment B is formed of an insulated box-like member 52, of which the freezing section 12^a of the evaporator forms the upper part. The freezing section 12^a of the evaporator is formed with an upper flat surface upon which ice trays or the like may be placed. The lower surface of the freezing section is formed of a plurality of U-shaped members arranged in spaced relation and clamped to the low-temperature coil of the evaporator. Box 52 which forms compartment B traverses substantially the entire width and depth of the refrigerator and is provided at its front with a hinged door 53. The arrangement is such that both the ice freezing compartment A and the low-temperature compartment B are insulated from the food storage compartment C. A gasket, not shown, may be placed between the door 53 of the low-temperature compartment and the door E of the refrigerator to further insulate compartment A from compartment C.

In operation, heat applied to the flue 20 of the generator causes expulsion of ammonia vapor out of solution. The vapor expelled from solution in chamber 14 accumulates in dome 17 and rises through conduit 18 causing upward flow of liquid through this conduit by vapor liquid-lift action into the upper end of standpipe 16. The vapor flows from the upper end of the standpipe

through conduits 21 and 22 into and upwardly through the analyzer 23, and from there the vapor flows through conduit 24 into the condenser 11. The vapor is liquefied in the condenser and the liquid refrigerant produced thereby flows therefrom through conduit 25 into one end of freezing section 12^a of the evaporator. Inert gas flows into the opposite end of freezing section 12^a and the liquid refrigerant and inert gas flow in counter-current relation in this section of the evaporator, whereby the liquid evaporates and diffuses into the inert gas with consequent absorption of heat from the evaporator and its surroundings, that is, from ice trays, for example, that are positioned upon the flat upper surface of this evaporator section and from the low-temperature compartment B below this evaporator section.

The mixture of inert gas and refrigerant vapor flows from section 12^a of the evaporator through conduit 40' into section 12^b of the evaporator wherein this mixture of gas and refrigerant vapor flows in concurrent relation with liquid refrigerant that flows from section 12^a into section 12^b through a conduit 12^c. In section 12^b of the evaporator liquid refrigerant evaporates and diffuses into the partially enriched inert gas, thereby cooling food storage compartment C, and the enriched inert gas passes from this section of the evaporator through conduit 41, outer passage 42 of the main heat exchanger, conduit 43, conduit 44 and absorber vessel 30 into the lower end of absorber 13.

In the absorber, the rich mixture of inert gas and refrigerant vapor is brought in contact with absorption solution that flows into the upper part of the absorber through conduit 29. The absorption solution flows from conduit 29 downward through section 13^a of the absorber thereby tending to push the inert gas toward conduit 34, whereby the flow of inert gas is started and continued in the proper direction, and the absorption liquid is conveyed from conduit 13^a through conduit 46 into the next lower conduit 13^b of the absorber. From there, the absorption liquid flows downward in the remainder of the absorber in counter-current relation to rich mixture of inert gas and refrigerant vapor flowing upward through that part of the absorber, whereby refrigerant vapor is absorbed into the absorption solution and the impoverished inert gas passes through conduit 34, outer passage 35 of gas heat exchanger 36, conduit 37, inner passage 38 of the main gas heat exchanger, and conduit 40, back to the low-temperature section 12^a of the evaporator.

Absorption solution rich in refrigerant vapor flows from the lower portion of the absorber into absorber vessel 30 and from there, the enriched absorption solution flows through conduit 31, conduit 32, analyzer 23, and conduit 33 into chamber 14 of the generator. In the generator refrigerant vapor is expelled from solution in chambers 14 and 15 and in standpipe 16. Refrigerant vapor expelled from solution in chamber 14 passes upward through vapor-lift conduit 18, as explained above, and the refrigerant vapor expelled from solution in chamber 15 and standpipe 16 passes upward through solution in the standpipe to the upper portion thereof from whence the vapor passes to the condenser, as explained above. The absorption solution weak in refrigerant is conveyed from chamber 15 through conduit 26, the lower part of conduit 21, conduit 27, and conduit 29 to the upper part of the absorber.

The arrangement shown particularly in Figs. 2

and 5 of the drawings is such that heat is transferred from the pressure vessel 47 and from a portion of conduit 25 through mounting plate 50 to air flowing upward through flue D. With this arrangement the pressure vessel and the conduit which conveys liquid refrigerant from the condenser to the low-temperature section of the evaporator may be placed within the closure member 51 so as not to obstruct the flow of air through flue D, while at the same time transferring heat from the pressure vessel and from conduit 25 to cooling air flowing upward in the flue. The liquid refrigerant is precooled further by placing a portion of conduit 25 in good thermal contact with the rich or cold side of gas heat exchanger 39.

While I have illustrated and described but one embodiment of my invention, the invention obviously may take other forms and be variously applied within the scope of the following claims.

What is claimed is:

1. In a refrigerator, a refrigerator cabinet including a food storage compartment, a flue at the rear of said compartment and an insulated closure member therebetween, and a refrigerating apparatus for cooling said food storage compartment, said refrigerating apparatus including a condenser within said flue and having a refrigerant vapor inlet and a refrigerant vapor and liquid refrigerant outlet, a pressure vessel within said closure member, an evaporator within said food storage compartment and having a liquid refrigerant inlet, conduits interconnecting said elements for flow of liquid refrigerant from the condenser to the evaporator, refrigerant vapor from the condenser to the pressure vessel and liquid refrigerant from the pressure vessel to the evaporator, and means including a portion of said closure member for cooling said pressure vessel, said pressure vessel being positioned within said closure member at an elevation below the level of the vapor and liquid refrigerant outlet of said condenser and above the level of the liquid refrigerant inlet of said evaporator, whereby condensate formed in the pressure vessel flows therefrom into the evaporator.

2. In a refrigerator, a refrigerator cabinet including a food storage compartment, a flue at the rear of said compartment and an insulated closure member between said compartment and said flue, and a refrigerating apparatus for cooling said food storage compartment, said refrigerating apparatus including a condenser within an upper portion of said flue, a pressure vessel within said closure member, an evaporator within said food storage compartment and conduits interconnecting said elements for flow of liquid refrigerant from the condenser to the evaporator, refrigerant vapor from the condenser to the pressure vessel and liquid refrigerant from the pressure vessel to the evaporator and means including a portion of said closure member for transferring heat from said pressure vessel to air flowing through said flue, said pressure vessel being positioned within said closure member at an elevation below the level of said condenser and above the level of said evaporator, the construction and arrangement being such that refrigerant vapor conveyed to the pressure vessel is condensed therein, the heat of such condensation is transferred to air flowing through the flue and the condensate formed in the pressure vessel is conveyed to the evaporator.

3. In a refrigerator, a refrigerator cabinet including a food storage compartment, a flue at

the rear of said compartment and a double wall closure member between said compartment and said flue, said double wall closure member including a metal plate which forms a part of said flue, and a refrigerating apparatus for cooling said food storage compartment, said refrigerating apparatus including a condenser in the upper portion of said flue, a pressure vessel within said closure member, an evaporator within said food storage compartment and conduits interconnecting said elements for flow of liquid refrigerant from the condenser to the evaporator, refrigerant vapor from the condenser to the pressure vessel and liquid refrigerant from the pressure vessel to the evaporator, said pressure vessel being positioned within said closure member at an elevation below the level of the lowermost part of said condenser and above the level of the uppermost part of said evaporator and in thermal contact with the metal plate of said closure member, the construction and arrangement being such that refrigerant vapor conveyed to the pressure vessel is condensed therein, the heat of condensation is transferred through the metal plate to air flowing through the flue and the condensate formed in the pressure vessel is conveyed to the evaporator.

4. In a refrigerator, a refrigerator cabinet including a food storage compartment, a flue at the rear of said compartment and a double wall closure member therebetween, said double wall closure member including a metal plate which forms a part of said flue, and a refrigerating apparatus for cooling said food storage compartment, said refrigerating apparatus including a condenser within an upper portion of said flue, a pressure vessel within said closure member, an evaporator within said food storage compartment, a first conduit connecting said condenser and said evaporator for flow of liquid refrigerant from the former to the latter and a second conduit connecting said first conduit and said pressure vessel for flow of refrigerant vapor to the pressure vessel and for flow of liquid refrigerant from the pressure vessel to said first conduit, said pressure vessel being arranged in said closure member below the level of said condenser and above the level of said evaporator and in thermal contact with the metal plate of said closure member, the construction and arrangement being such that refrigerant vapor conveyed to the pressure vessel is condensed therein, the heat of such condensation is transferred through the metal plate to air flowing through the flue and the condensate formed in the pressure vessel is conveyed to the evaporator.

5. In a refrigerator, a refrigerator cabinet including a food storage compartment, a vertical flue at the rear of said food storage compartment and a double wall closure member between said food storage compartment and said vertical flue, and a refrigerating apparatus for cooling said food storage compartment, said refrigerating apparatus including a condenser located in the upper portion of said flue, a pressure vessel located within said closure member, an evaporator located in said food storage compartment and a conduit leading from an outlet of said condenser to an inlet of said evaporator, said conduit having a portion thereof in thermal contact with one of the walls of said closure member.

6. In a refrigerator, a refrigerator cabinet including a food storage compartment, a vertical flue at the rear of said food storage compartment and a double wall closure member between said

food storage compartment and said vertical flue, and a refrigerating apparatus for cooling said food storage compartment, said refrigerating apparatus including a condenser located in the upper portion of said flue, a pressure vessel and a gas heat exchanger located within said closure member, an evaporator located in said food storage compartment and a conduit leading from an outlet of said condenser to an inlet of said evaporator, said conduit having a portion thereof in thermal contact with one of the walls of said closure member and another portion thereof in thermal contact with said gas heat exchanger.

7. In a refrigerator, a refrigerator cabinet including a food storage compartment, a vertical flue at the rear of said food storage compartment and a double wall closure member between said food storage compartment and said vertical flue, and a refrigerating apparatus for cooling said food storage compartment, said refrigerating apparatus including a condenser located in the upper portion of said flue, a pressure vessel and a gas heat exchanger located within said closure member, an evaporator located in said food storage compartment and a conduit leading from an outlet of said condenser to an inlet of said evaporator, said conduit having a portion thereof in thermal contact with one of the walls of said closure member and another portion thereof in thermal contact with said gas heat exchanger, said pressure vessel comprising a horizontally elongated member arranged in thermal contact with the one wall of said closure member.

8. In a refrigerator, a refrigerator cabinet including a food storage compartment, a vertical flue at the rear of said food storage compartment and a double wall closure member between said food storage compartment and said vertical flue, and a refrigerating apparatus for cooling said food storage compartment, said refrigerating apparatus including a condenser located in the upper portion of said flue, a pressure vessel and a gas heat exchanger located within said closure member, an evaporator located within said food storage compartment, a first conduit leading from an outlet of said condenser to an inlet of said evaporator, said first conduit having a portion thereof arranged in thermal contact with one of the walls of said closure member and another portion thereof in thermal contact with said gas heat exchanger, said pressure vessel comprising a horizontally elongated member arranged in thermal contact with the said one wall of the closure member and positioned at an elevation below the level of the outlet of the condenser and above the level of the inlet of the evaporator, a second conduit connecting said pressure vessel to said first conduit and a third conduit connecting said pressure vessel to the gas heat exchanger, substantially the entire length of each of said conduits being within said closure member.
